CLAIM

The ornamental design for a masonry cutter hammer, as shown and described.

DESCRIPTION

FIG. 1 is a front perspective view.

FIG. 2 is a rear perspective view.

FIG. 3 is a front view.

FIG. 4 is a rear view.

FIG. 5 is a right side view.

FIG. 6 is a left side view.

FIG. 7 is a top view; and,

FIG. 8 is a bottom view.

1 Claim, 6 Drawing Sheets
